UNITED STATES PATENT OFFICE.

JOSEPH GEORGE DAVIDSON, OF PITTSBURGH, PENNSYLVANIA, ASSIGNOR TO C. H. CONNER, OF NEW YORK, N. Y.

METHOD AND APPARATUS FOR CRACKING OILS.

Application filed November 30, 1921. Serial No. 518,786.

To all whom it may concern:

Be it known that I, JOSEPH GEORGE DAVIDSON, a citizen of the United States, residing at Pittsburgh, in the county of Allegheny, State of Pennsylvania, have invented certain new and useful Improvements in Methods and Apparatus for Cracking Oils; and I do hereby declare the following to be a full, clear, and exact description of the invention, such as will enable others skilled in the art to which it appertains to make and use the same.

This invention relates to an improved method and apparatus for the thermal decomposition or cracking of oils, such as the higher boiling petroleum fractions, etc., for the production therefrom of gasoline and other products.

More particularly the present invention relates to improvements in the thermal decomposition or cracking of oils with internal heating of the oil by electrically heated resistors submerged therein.

The successful cracking of oils by heating the oils internally with electrically heated resistors requires the use of resistors which will carry a heavy current. In using large carbon resistors to heat the oil I have found that a deposit of carbon takes place on the resistors which increases their cross section, thereby reducing the resistance and permitting an increased current to flow. If this deposit is permitted to increase to any considerable extent, I have found that it is practically impossible to separate it from the resistors without breaking the resistors and making them unavailable for further use, thus making necessary the provision of new resistors of appropriate size for the further carrying out of the process. This injury to the resistors is apparently due to the heavy and firmly adherent layer of carbon formed around the resistor and to the heating of the resistor itself to a higher temperature than that of the surrounding carbon layer, so that, when the resistor is cooled the tendency of the resistor to contract is resisted by the surrounding carbon layer with resulting cracking of the resistor transversely, due to the excessive tension caused by the contraction.

According to the present invention, instead of using large resistors and attempting to remove the objectionable carbon deposit therefrom, I take advantage of this carbon

deposit and utilize it in forming a resistor of appropriate size within the body of the oil. In order to take advantage of this carbon deposit, I make use of a small resistor as a nucleus and I so carry out the heating of the resistor and of the oil that the deposit of carbon, which, at first, is of a somewhat mushy consistency, undergoes further change upon continued heating and forms a resistor of increasing size. In conjunction with this building up of the resistor upon a small nucleus I make use of suitable regulating means that will so reduce the voltage as the area of the resistor increases that the input (that is, the voltage times the current) remains constant so as to maintain practically a constant heating of the oil during the cracking process. That is, as the resistance of the resistors decreases, due to building up of the size of the resistors, I reduce the voltage so as to obtain the desired heating effect, thereby avoiding the greatly increased heating effect which would result with increased current at the same voltage.

The present invention accordingly avoids the necessity for removing the deposited carbon, deposited during the cracking operation, but takes advantage of this deposit for producing the resistors themselves which are used in the carrying out of the cracking operation. The provision of expensive resistors of large size at the outset of the process is thus made unnecessary. At the end of the cracking operation, and after the resistors have so increased in size that they cannot be further used advantageously in the process, they can be broken up and utilized for the carbon which they contain, and additional resistors can be built up in the manner above described, for use in the further carrying out of the cracking operation.

In the practice of the invention I make use of relatively thin or small rods or bars as nuclei, and I provide the cracking still with means for supporting these rods or bars and for supplying a heavy current thereto, and I space these nuclei apart so as to permit the building up of relatively large and heavy resistors therefrom without short circuiting.

In conjunction with the cracking still I also provide means for varying and regulating the current so that, as the resistors increase in size, and as their resistance de-

creases, a substantially constant or regulated heating effect can nevertheless be obtained.

The nature and advantages of the invention will more fully appear from the following more detailed description, taken in connection with the accompanying drawings illustrating one form of apparatus embodying the invention and adapted for the carrying out of the process of the invention.

In the accompanying drawings, Figure 1 is a diagrammatic illustration in central vertical section of one form of apparatus;

Fig. 2 is a plan view of the still of Fig. 1;

Fig. 3 is an enlarged sectional view taken on the line 3—3 of Fig. 1; and

Figs. 4 and 5 are enlarged detail views showing how the resistors may be held in place.

In the apparatus illustrated the cracking still 1 is of the horizontal type and of suitable size to contain a relatively large body of oil. The size of the still is capable of considerable variation and stills may be used having, for example, a capacity of as much as two thousand gallons or more.

The still illustrated has a suitable valve-controlled inlet pipe 2 for introducing oil and a valve-controlled outlet pipe 3 for withdrawing the residue from the still. It also has a reflux column or tower or diphlegmator 4 operating in a manner which will be readily understood. End covers or heads 5 are provided through which access may be had to the inside of the still. A pyrometer well 7 is also provided

for enabling the temperature of the oil to be ascertained. The apparatus may in practice be provided with a condenser (not shown) for condensing the distillate, means for maintaining the desired pressure in the

still and in the condenser, and means for supplying a regulated supply of oil to the still either in the form of successive charges or progressively during the cracking process. The oil may also be preheated, if de-

sired, before it is introduced into the still. It will be evident that the oil should be forced into the still at a pressure corre-

sponding to that maintained within the still. The still is well adapted for use at high pressures inasmuch as the still walls are protected from direct heating by the heating means employed, so that they are not weakened, as are the common externally heated stills. The distillate may be con-

duced either under the same high pressure as that of the still or under a lower pressure. The still is provided with resistors adapted to be heated by a three-phase alternating current. One suitable means of

introducing the current and of connecting

the resistors is illustrated in Fig. 3. The still is provided with an opening 8 arranged with a stuffing-box and tapered to accommodate the concentrically arranged conical members 9, 10 and 11 to which the leads 70 of the three phases of the current are connected, and which are insulated from each other and from the still walls by suitable insulating means arranged, for example, in the manner illustrated.

This arrangement of the leads reduces hysteresis losses to a minimum. Furthermore, the necessity of spreading three stuffing boxes on the top of the still is avoided, the stuffing box shown being only slightly 80 larger than would be necessary for each lead if they were brought in separately. By

constructing the leads 9 and 10 as cylindrical or frustro-conical shells 1 utilize the so-called "skin effect" which causes alternating currents to flow at or near the surface of the conductor, the central portions of the said conductor carrying only a very small portion of the total current. The supporting and connecting members 12, 13, 14 and 15 are united, respectively, to the members 9, 10 and 11 and are connected at their lower ends with the supports 15 of the rods 16, one of which is illustrated in Fig. 4. At their other ends, the rods 16 are supported on supports 17 which are in turn supported from the still walls by the conducting cross bar 18 and the insulating upright bars 19, and the members 17 are electrically connected together by the cross bar. A modified form of support for holding two superposed rods 24 (instead of one rod 16) is illustrated in Fig. 5, in which the base member 17a has a depression 90 for receiving the lower half of one of the rods and the upper member 25 is secured thereto by bolts 23 and is also so shaped as to receive the upper rod 24 and hold it in place by means of the pins 27 operating in openings in the member 25. In order to 100 prevent carbon deposit upon the heads of the screws 23 and to permit ready removal of these screws even after a deposit of carbon has taken place on the rods 24, insulating caps 26 may be arranged over the heads 105 of these screws.

It will thus be seen that the construction is such that the rods 16 can be readily inserted and held in place and also such that, when the resistors have been built up to a large size around the rods 16, they can nevertheless be broken away from the supports and further nuclei rods inserted. In inserting these rods a cementing material for example, a mixture of powdered 110 graphite and molasses may be used which, upon passage of the current, gives a good electrical connection between the rods and their supports through which the current is supplied.

In order to permit a deposit of carbon to be formed upon the nuclei rods and to increase so as to form large resistors, the nuclei rods or bars are spaced apart from the still walls and from each other so that the carbon deposit will be prevented from bridging across until the resistors have increased to a large size.

In the operation of the apparatus and the carrying out of the cracking operation I introduce one or more thin rods or bars, depending upon whether an alternating or direct current is used, or whether a single-phase or polyphase alternating current is used, and connect these rods with the leads for the electric current, for example, in the manner illustrated and above described. By using as a nucleus or as nuclei a thin rod or rods of about one inch in diameter by eighty inches long, these rods can be heated by the use of a heavy current so that a layer of carbon will begin to build up on the rods quite rapidly. This carbon deposit will result in an increase in the current conducting area of the rod. As the diameter of the rod increases, due to the deposit of the conducting carbon, the voltage can be lowered to maintain a constant load, that is, the voltage can be lowered as the current increases, this latter being due to the decrease in resistance, so that the heating effect will remain approximately constant or within predetermined limits. The process can be continued in this way until the deposit of carbon upon each rod becomes thick enough to cause short-circuit. The accumulated carbon of the resistors can then be removed and further nuclei introduced.

The regulation of the current can be effected by suitable regulating means, and this regulation may be automatic in character. For example, a transformer may be used with regulation of the voltage so that the voltage will drop as the size of the resistor increases, so that the heating effect, due to the current supplied, will be maintained practically uniform or within the desired limits. If, for example, a current is initially supplied of 2,000 amperes at 100 volts, the voltage can be decreased in proportion to the decrease in resistance so that, with a current of 4,000 amperes, the voltage will be reduced to about 50 volts. At the outset a current of from 200 to 1000 amperes per square inch of cross section may be used at a voltage of from 100 to 200 volts. As the cracking operation proceeds and the deposit of the carbon increases the cross section of the nuclei and thereby decreases their resistance, a current of increased amperage will tend to pass at approximately the same voltage, but by the use of suitable electric apparatus the voltage can be decreased as the amperage increases so that the heating effect will be

substantially constant, that is, the input of energy will remain approximately constant and therefore the rate of cracking or of distillation of the oil will remain practically constant or uniform.

It will thus be seen that the present invention provides for the carrying out of the cracking operation with regulation and control of the operation, and that advantage is taken of the carbon deposit formed during the cracking operation to produce, within the body of oil, the resistors which are used in the carrying out of the cracking operation, it being necessary merely to provide nuclei at the outset upon which the building up of the resistors will take place.

From another viewpoint, it may be considered that the present invention involves the production of carbon from petroleum of such a character that it is well adapted for use in making carbon resistors. That is, the carbon deposited on the nuclei and which forms the resistors during the cracking operation, is sufficient in amount so that, at the end of the cracking operation, and when the resistors have built up to such a degree that they are to be removed, a considerable amount of carbon is provided which can be broken up and used for electrical or other purposes, for example, in the making of the nuclei rods or bars used in the process.

I claim:

1. The method of cracking oils with internal electrical heating of the oil which comprises supplying the current initially through nuclei resistors and causing the resistors to build up by carbon deposits thereon during the cracking operation, regulating the electric current and decreasing the voltage as the cross sectional area of the electric resistors increases.

2. The process according to claim 1, in which a plurality of nuclei resistors are used and in which the current is supplied as polyphase alternating current to such resistors.

3. The process according to claim 1, in which the voltage is so regulated with increase in size of the resistors that a substantially constant heating effect is obtained.

4. An apparatus for cracking oil comprising an oil cracking still, relatively thin nuclei resistors of carbon therein, means for detachably securing the resistors in the still and for supplying electric current thereto, and means for supporting the nuclei resistors away from each other and away from the walls of the still to permit the formation of relatively thick resistors thereon by deposition of carbon.

5. An apparatus for cracking oil comprising an oil cracking still, relatively thin nuclei resistors of carbon therein and means for supporting the nuclei resistors away

- from each other and away from the walls of the still to permit the formation of relatively thick resistors thereon by deposition of carbon, means for detachably securing 5 the nuclei resistors in the still and for supplying electric current thereto, and means for reducing the current flowing through the resistors as the cross sectional area of the resistors increases.
- 10 6. An apparatus for cracking oils comprising an oil cracking still having a plurality of small nuclei resistors therein, detachable means for supporting said resist-

ors, means for supplying alternating current to said resistors comprising a 15 plurality of insulated leads introduced through a single opening in the still, and said resistors being spaced apart to permit the building up of carbon thereon progressively during the cracking operation until 20 large massive resistors are formed by such deposit.

In testimony whereof I affix my signature.

JOSEPH GEORGE DAVIDSON.
